LIGHTING FIXTURE

Eduard R. Huegel, Brooklyn, N. Y., assignor to
 Rambusch Decorating Company, New York,
 N. Y., a corporation of New York

Application March 15, 1946, Serial No. 654,716

3 Claims. (Cl. 240—73)

1

The present invention relates to lighting fixtures and is more particularly directed toward such fixtures adapted for wall mounting and to produce indirect lighting.

The present invention contemplates the employment of a projector type lamp bulbs mounted on an axis about 45° to the horizontal, base down. Such lamps have an annular reflector which projects the dominant beam along the axis of the lamp for flood or spot lighting and allows the escape of direct light through an angle of about 115° about the lamp axis. The light emitting face of the lamp is flattened and etched to render it diffusing. While such a lamp mounted in this position is well adapted to be a source of indirect light, it is unsuited for use bare, for considerable of the direct light is at such low angles as to strike very remote ceiling areas and opposite wall areas, also direct light as well as scattered light from the etched surface is at such low angles as to be in the normal field of vision.

The present invention contemplates fixtures wherein the lamp bulb is received in an enclosure which not only provides an ornamental appearance to the unlighted fixture, but also, without substantially interfering with the escape of the reflected beam, provides for the screening of all light rays below the horizontal through the top of the lamp, and allows the escape of direct light below the reflected beam.

According to the present invention the direct light is so controlled as to reduce the light emitted toward the adjacent or supporting wall as to provide a minimum of back splash onto the wall.

The accompanying drawings show, for purposes of illustrating the present invention, an embodiment in which the invention may take form, it being understood that the drawings are illustrative of the invention rather than limiting the same.

In these drawings:

Figure 1 is a vertical sectional view through a lighting fixture taken in planes at right angles to the wall on which it is supported;

Figure 2 is a front elevational view with parts in section on the line 2—2 of Figures 1 and 3;

Figure 3 is a top plan view with parts in section;

Figure 4 is a perspective view on a small scale illustrating a fixture as it appears at ordinary angles of observation;

Figure 5 is a diagrammatic view illustrating the positioning of the fixture on the wall relative to the ceiling; and

2

Figure 6 is a diagrammatic view illustrating the region on the ceiling illuminated by the fixture.

In the drawings a supporting wall is indicated at 10 and ceiling at 11. The fixture is mounted on the wall so as to be above the ordinary line of vision and a suitable distance below the ceiling. As shown in the drawings the fixture body 12 is in the form of a casting. The casting has an ornamental top portion 13 and an ornamental lower portion 14 which extends forwardly from the wall, this portion 14 having vertical side walls 14a, 14b and front wall 14c. The upper edges of the walls 14a, 14b and 14c and the lower edge of the top portion have a configuration which places them on the surface of a sphere struck from the center 15.

The casting receives a spun metal bowl 20, preferably of spherical contour having its center at 15 and adapted to be secured to the casting by screws indicated at 21. The bowl carries an angle bracket 22 which supports a lamp socket 23 on an angle of substantially 45° to the vertical. This socket is adapted to support a projector type incandescent lamp 25 such as the 300 watt R40 flood or R40 spot lamp.

This lamp has a concentrated filament indicated at 26, a generally parabolic reflector portion 27 which will project a concentrated beam of light upwardly with its axis at 45° to the horizontal. The mouth of the reflector is indicated at 28 and hence the lamp also limits direct light in a cone of an angle determined by the position of the filament and the mouth of the reflector. The end of the lamp is flattened as indicated and etched at 29. The projected beam of light rays of moderate divergence is indicated at dash lines 30. The direct light is indicated by solid lines 31 and the angle of spread of the cone of direct light is indicated as about 115°. The diffused and scattered light from the end of the bulb is indicated by short, arrowed lines 32.

The concentrated beam of reflected light indicated by the rays 30, is directed toward an elliptical area 34 on the ceiling as indicated in Figure 6. The extreme upper direct rays such as ray 31a, are slightly past the zenith and will strike the supporting wall some distance above the fixture. The lowermost direct rays such as 31b, are below the horizontal, and if the lamp were used in this position without any enclosure the direct light would spread across the ceiling and down onto any opposite side wall, and, in planes adjacent the normal to the supporting wall, would continue down below the horizontal. Also, the end of the lamp would scatter light

throughout somewhat more than a hemisphere, so that from whatever angle the lamp were likely to be viewed, the bright end of the lamp would be in the line of vision.

According to the present invention the bowl 20 which receives the lamp, is designed to control the light which would be otherwise emitted in unwanted directions. The portion of the bowl 20 between the vertical axis 2-2 passing through the center 15 and the fixture body is slightly deeper than the hemisphere so that the extreme upper surface of the lamp bulb is below the upper edge 35 of this portion of the bowl. The front half of the hemispherical spinning employed in making the bowl is cut back as indicated at 36 to be in a plane at right angles to the wall, at an angle of approximately 20° above the horizontal through the light center. This portion of the bowl receives direct light rays below the horizontal and above the horizontal up to the cut-off line provided by the upper outer edge of the front of the bowl and reflects such of these light rays as are not absorbed.

The lateral opening in the hemispherical bowl, formed by cutting away the upper front portion of it, is occupied by two louvers 37 and 38. These louvers are made of metal and the upper louver is on edge toward the center of the lamp. The upper edge 39 of the upper louver is on the same level of the upper edge 35 of the bowl and its lower edge 40 is even with the upper edge 41 of the lower louver. The lower louver is for manufacturing reasons, made like the upper louver. The angle of these louvers in the plane of Figure 1, is approximately 32°. Owing to the fact that the light center 26 is here shown as offset from the vertical 2-2 through the center 15, the baffles 37 and 38 are not true cones but are generally conical. They are slightly steeper as they approach the wall as indicated in Figure 2. These louvers may be fastened to the bowl in any suitable manner, the details of which are omitted from the drawings.

The louvers permit a very large portion of the direct and reflected light from the lamp to pass outwardly at angles above 20° above the horizontal and reach portions of the ceiling beyond the more brightly lighted area 34. The light rays, however, do not extend over onto extremely remote ceiling areas or onto the opposite side wall. Also, all scattered light emitted by the lamp at angles below the horizontal is intercepted by either the baffles or the upper part of the hemispherical bowl so that no matter in what azimuth one views the fixture in positions below the upper edge of the bowl, no sources of brightness exist except the lower surfaces of the louvers 37 and 38. The brightness of these may be controlled by suitably darkening the upper surface of the lower baffle and the lower surface of the outer part of the bowl which would reflect light onto the lower baffle.

Not only are there no annoying bright elements in view, but the arrangement shown is one which reduces the amount of light emitted on the wall side of the vertical, so as to be capable of falling on the adjacent side wall. The only light which can strike the side wall immediately above the fixture is that which is diffusely transmitted from the upper part of the etched surface of the bulb. A small amount of direct light strikes the ceiling some distance above the fixture so that the annoying bright back splash of light ordinarily obtained from wall fixtures is substantially reduced.

Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

What is claimed is:

1. A luminaire comprising a projector type lamp having a reflector to project light in a narrow concentrated beam and positioned to allow the escape of direct light through a cone with an apex angle of substantially 115°, the end of the bulb of the lamp beyond the reflector being flattened and having a light diffusing etching, means for mounting the lamp with its axis at substantially 45° to the horizontal, a bowl in which the lamp is received, the bowl being of generally hemispherical shape with its upper edge slightly above the top of the lamp and its deepest part slightly below the bulb of the lamp, the upper forward portion of the bowl being removed to provide a lower front edge, and louvers generally conical about a vertical axis in front of but adjacent the filament of the lamp and above and in front of the bulb and of the same outside radius as the top of the bowl for permitting escape of direct light at angles above the horizontal and cutting off light below the horizontal which would otherwise escape over the lower front edge of the bowl.

2. An indirect lighting fixture mounted adjacent a vertical wall and having a projector lamp mounted on an axis at substantially 45° to the vertical so that the projected beam is receivable on the ceiling in a generally elliptical area whose center is distant from the wall substantially the distance the fixture is below the ceiling, the lamp also delivering direct light in a wide angle cone about the projected beam such that direct light is received on the upper portion of the adjacent side wall, on the ceiling about the elliptical area, and is emitted at angles too low to reach the ceiling and in the normal line of vision, and an upwardly opening bulb enclosure including an opaque bowl which extends about the bulb in all azimuths, up to the level of the top of the bulb in a substantially 180° zone on the side toward the wall and up to a level substantially 20° above the horizontal through the light source in the front 180° zone to provide a 20° cut-off angle for direct light therein, and a plurality of louvers occupying the region between substantially said cut-off angle and up to a level slightly above the uppermost part of the lamp, the louvers being edgewise to the light center of the lamp and acting in said zone at all angles below the horizontal, to screen parts of the lamp not screened by the bowl.

3. An indirect lighting wall type lighting fixture having a housing for mounting on a vertical wall surface, an incandescent lamp socket fixedly carried by the housing with its axis substantially 45° above the horizontal, a socket carried incandescent lamp having a filament spaced substantially from the wall, a parabolic reflector for projecting reflected light toward the ceiling at substantially 45° above the horizontal, the lamp having a flattened diffusing end across the mouth of the reflector for transmitting direct and reflected light and providing a corresponding projected area of brightness when viewed horizontally, the mouth of the reflector being so spaced from the filament that direct light escapes in a cone of substantially greater than 90°, where-

by in the plane normal to the wall through the lamp axis the lower bounding direct rays are below horizontal and the upper bounding direct rays are directed toward the wall at near to the zenith, and a housing carried bowl-shaped enclosure of a vertical depth to receive the reflector and diffusing mouth of the lamp and screen the mouth of the lamp at all azimuth angles up to the horizontal through the top of the lamp, the upper portion of the front of the enclosure including conical louvers occupying a horizontal angle of substantially 180° about a vertical axis in front of but adjacent the lamp filament and a depth equal to substantially one-half the vertical depth of the diffusing end of the sloping lamp, the enclosure being opaque below and to the rear of the louvers, and wherein the top of the front opaque portion of the enclosure is sub-

stantially 20° above the horizontal through the filament.
